UNITED STATES PATENT OFFICE.

WILLIAM A. BENSON, OF CHICAGO, ILLINOIS, ASSIGNEE TO AUTOMATIC ELECTRIC COMPANY, OF CHICAGO, ILLINOIS, A CORPORATION OF ILLINOIS.

AUTOMATIC TELEPHONE SYSTEM.

Application filed July 26, 1921. Serial No. 487,802.

To all whom it may concern:

Be it known that I, WILLIAM A. BENSON, a citizen of the United States of America, and a resident of Chicago, Cook County, and State of Illinois, have invented certain new and useful Improvements in Automatic Telephene Systems, of which the following is a specification.

The present invention relates to automatic telephone systems in general, but is concerned more particularly with such systems as include toll or long distance lines in addition to the local subscribers' lines; and the object, broadly stated, is the provision of novel and improved circuit arrangements to be used by a toll operator for connecting toll lines with local subscribers' lines.

In a modern automatic telephone system it is common practice to provide toll switches which, together with their inter-connecting trunk lines, form what is known as a toll service trunking system, through the medium of which the local toll operator extends all toll calls, both incoming and outgoing, to the local subscribers' lines. It is the usual practice to connect the toll lines with the toll service trunks by means of cord circuits. It is easily seen now that in such systems since every call, whether incoming or outgoing, must be extended by way of a toll line, a cord circuit, and a toll service trunk, aside from having them in reserve to take care of one or more getting out of order, nothing is gained by making either the toll service trunks or the cord circuits greater in number than the toll lines, and vice versa. Accordingly an arrangement is contemplated whereby each toll service trunk line is made individual to a toll line, the cord circuits being replaced by permanently associated links which connect each toll line with a toll service trunk line.

The above indicates in broad terms the scope of the invention; however, various features included in the working of the complete system will not now be specifically mentioned, but will be described fully in the course of the specification and pointed out in the appended claims.

Referring now to the drawings, which comprise Figs. 1 and 2, in order to enable them to be understood best, Fig. 2 should

be placed directly over Fig. 1 with the corresponding lines in alignment. When laid out thus they represent diagrammatically sufficient of the equipment in the toll office, in a system of the type described, to enable the invention to be understood.

Referring now particularly to Fig. 1, the toll line X, shown in the lower left-hand corner thereof, is one of a number of toll lines which may be terminated in the toll office of the system. As shown, the toll line X extends through, by way of the permanently associated link designated by the reference character O, and the automatic repeater E, to the talking conductors 89 and 91 of the toll service trunk comprising conductors 89—91, inclusive. This toll service trunk is assumed to extend to and terminate in a toll first selector belonging to the previously mentioned toll service trunking system. Such a trunking system is completely disclosed in the United States patent to Wicks No. 1,815,444, granted September 9, 1919.

Referring now to Fig. 2, the jacks J and J' are associated with the operator's position at which the link circuit O is located and, together with a small number of cord circuits of which the cord circuit O' is one, are used for the purpose of making emergency connections as will be hereinafter explained. The jacks J² and J³, which are multiples of the jacks J and J', respectively, are located at the night operator's position. This operator has a number of cord circuits, each of which is a duplicate of the cord circuit O', by means of which she connects the toll lines with the toll service trunks.

It has been found many times in actual practice that the night operator, who in many systems has other duties to perform besides extending toll calls, is likely to have need of a greater number of cord circuits of the so-called loop dialling type than she has of the so called simplex or grounded impulse type of cord circuit. Assuming that such is the case, all the cord circuits are arranged for loop dialling and the repeater E, shown in Fig. 1, is interposed between the jacks J' and J² and the toll service trunk comprising conductors 89—91, inclusive, and among other things translates loop dialling impulses into grounded impulses.

The operator's head set, which is shown in the upper part of Fig. 1, is provided with a set of listening and monitoring taps and is further arranged for loop impulse dialling when the operator is using a cord circuit and for grounded impulse dialling when the operator is extending a connection by way of the link circuit O or a similar circuit.

The apparatus, having been described more or less in general, will now be described in connection with a detailed description of its operation. For this purpose it will be assumed that a call comes in over the toll line X. In response to the ringing current coming over the toll line X, ring up relay 11, which is connected in bridge of the toll line X by way of the back contacts of armatures 22 and 23 and said armatures of cut-off relay 12, energizes and becomes locked up mechanically by an interlocking arrangement (not shown) between the armature of the said relay 11 and the armature of cut-off relay 12. A structure of this nature is disclosed in the co-pending application of Erickson, Serial No. 461,760, filed April 16, 1921. As a result of the operation of relay 11, it places ground on conductor 68 at armature 20, thereby lighting the busy lamp L² associated with the link circuit O and also the busy lamps L³ and L⁷ associated with the jacks J and J², respectively. A branch of this circuit extends by way of armature 21 of cut-off relay 12 and its resting contact, conductor 70, the spring of the lamp switching key associated with the jack J² and its resting contact, conductor 69, and line lamp L to battery.

The operator, upon noting the lighted condition of the line lamp L, throws her key K² into listening position, thereby operating the springs 100-103, inclusive. Springs 101 and 102, upon being operated, connect the operator's head set in bridge of the heavy talking conductors, while spring 103, upon being operated, closes a circuit for release relay 10 by way of the lower pair of contacts of the release push button P. A branch of this circuit extends to battery through the holding lamp L' which becomes lighted. Upon energizing, release relay 10 closes a locking circuit for itself at armature 17 and at armature 18 closes the following circuit for cut-off relay 12: from ground by way of armature 27 and its resting contact, armature 26 and its resting contact, armature 18 and its working contact, and cut off relay 12 to battery. Upon energizing, cut off relay 12 removes ring up relay 11 from in bridge of the heavy talking conductors at armatures 22 and 23, while at armature 21 it removes ground from conductor 70, thereby extinguishing the line lamp L, at the same time placing a multiple ground on conductor 68 so as

to maintain the busy lamps L², L⁷ and L³ lighted after the ring up relay 11, which is unlocked mechanically by the pulling up of cut off relay 12, has fallen back.

The answering operator now converses with the calling operator and after ascertaining the desired number throws the key K³ into calling position, thereby operating the springs 105-109, inclusive. Spring 109, upon being operated, closes a circuit for release relay 13 which, upon energizing, locks itself to ground at armature 25 through the upper pair of contacts of the release push button P, and prepares a circuit for the marginal supervisory relay 16 at armature 24. As a further result of the operation of key K³, ground is placed on conductor 64 at spring 108 and its working contact, thereby closing a circuit for the calling device switching relay 50 of the operator's head set. Upon energizing, relay 50 removes the impulse springs of the calling device S from the loop control circuit comprising conductors 60 and 61 and places it in the ground impulse control circuit which may be traced as follows: from ground by way of armature 53 and its working contact, impulse springs of the calling device S, working contact of armature 52 and said armature, conductor 65, spring 106 of key K³ and its working contact, conductor 85, and the resting contact of armature 44 and said armature, to the control conductor 90 of the toll service trunk comprising conductors 89-91, inclusive. This control conductor 90 extends to and terminates in the line relay of a toll first selector, the other terminal of the said line relay being connected to the ungrounded pole of the exchange battery. Accordingly the line and release relays of the said toll first selector immediately energize and prepare the switch for operation.

The operator may now manipulate the calling device S in accordance with the digits of the desired number, whereupon the switches of the toll service trunking system are operated in the usual manner to extend the connection to the desired line.

After having finished dialling the number, the operator throws the key K³ to the opposite or ringing position, whereupon the springs 105-109, inclusive assume normal position, the calling device switching relay 50 of the operator's head set becomes de-energized, and the switch control circuit is transferred from ground, by way of conductor 64, to ground by way of armature 24 and its working contact and the marginal supervisory relay 16. Supervisory relay 16, upon energizing, closes a circuit for supervisory lamp L⁴ by way of armature 40 and its resting contact, and the said lamp becomes lighted.

As a further result of the throwing of key

K^3 to ringing position, ringing current is sent out over the established connection thereby ringing the called subscriber's bell until the said key is returned to normal position.

When the called subscriber answers the circuits of the automatic switches are automatically put into talking condition and in order to notify the operator, a high resistance is automatically inserted into the operating circuit, whereupon the marginally adjusted supervisory relay 16 deenergizes, extinguishing the supervisory lamp L^4 .

The calling subscriber may now converse with the called subscriber, assuming of course that the calling operator has in the meantime extended the connection to the calling subscriber by way of the other end of the toll line X .

When the conversation is finished the two subscribers replace their receivers. When the receiver is replaced at the called substation, the before mentioned high resistance is removed from the control circuit, whereupon supervisory relay 16 energizes again and lights the supervisory lamp L^4 .

When the calling operator, or the operator that originated the connection, gets the disconnect signal from the calling subscriber, she momentarily projects ringing current out over the toll line X , thereby operating the ring up relay 14 which is connected in bridge of the toll line X by way of spring 100 of key K^2 and its resting contact, and the working contact of armature 19 and the said armature of release relay 10. Upon energizing, ring up relay 14 removes at armature 26 a shunt which is normally around relay 15, whereupon relay 15 energizes in series with cut off relay 12 and at armature 27 opens another point in said shunt, at the same time lighting the supervisory lamp L^3 .

When the operator sees the lighted condition of the supervisory lamps L^3 and L^4 she knows that the conversation is finished and that the subscribers have replaced their receivers. In order to release the automatic switches and to remove the busy signal from the toll line X , the operator momentarily operates the release push button P , thereby unlocking the release relays 10 and 13. Release relay 10, upon deenergizing opens its own locking circuit at armature 17, thereby preventing it from energizing again and extinguishing the holding lamp L' . As a further result of the deenergization of release relay 10, it opens the circuit of cut off relay 12 at armature 18, whereupon the said cut off relay 12 and relay 15 deenergize. The supervisory lamp L^3 together with the busy lamps L^2 , L^5 and L^6 now becomes extinguished. Release relay 13, upon deenergizing, opens the switch control circuit at armature 24, whereupon

supervisory relay 16 deenergizes and extinguishes the supervisory lamp L^4 . As a further result of the opening of the control circuit, the automatic switches are released in the usual manner. All the apparatus used in extending the connection is now restored to normal and ready for another call.

We shall now assume that the toll operator is authorized to set up a connection which must be extended by way of a toll line of the group to which the toll line X belongs. Assuming that the operator decides to use the toll line X , the said toll line being idle, as indicated by the unlighted condition of the busy lamp L^2 , the operator throws the key K^2 into listening position, thereby connecting her head set in multiple with the toll line; lighting the holding lamp L' and operating the release relay 10 and cut off relay 12 in the usual manner. As a result of the operation of cut off relay 12 the busy lamps L^2 , L^3 , and L^4 obviously become lighted and the ring up relay 11 is removed from in bridge of the toll line.

The operator now throws the key K' in such a direction as to project ringing current out over the toll line X , thereby operating the ring up relay on the other end of the said toll line. When the operator on the other end of the toll lines responds, the calling operator gives her the number and requests her to extend the connection to the called subscriber.

The calling operator now extends the connection to the calling subscriber by way of the toll service trunk comprising conductors 88—90, inclusive, in the usual manner.

After the connection is completed the calling and called subscribers may converse with each other as desired; and at the termination of the conversation they both replace their receivers.

When the receiver is replaced at the calling substation the supervisory lamp L^4 is lighted in a manner hereinbefore described.

When the operator notes the lighted condition of lamp L^4 , she momentarily operates the key K' so as to send ringing current out over the toll line to operate the disconnect signal on the other end, and releases the connection by momentarily operating the release push button P .

As has been mentioned before the toll operator, in addition to a number of link circuits such as link circuit O , is provided also with a small number of cord circuits such as cord circuit O' . Now in case one of the toll service trunks, the toll service trunk comprising conductors 89—91, inclusive, for example, is temporarily out of order, the associated toll line is not tied up, for the operator who may be provided with one or two extra toll service trunks may insert one plug of a cord circuit into the toll line jack, such as the jack J , and insert the other plug of the cord circuit

into the jack of one of the extra toll service trunks, which jack is similar to the jack J' . It may be stated that each of the reserve toll service trunks may be equipped with only so much of the equipment shown in Fig. 1 as is necessary.

Assuming, for the purpose of illustration, that the operator receives a call over the toll line X and finds that the associated toll service trunk is out of order, she manipulates the push button P , thereby restoring the circuit condition of the relays associated with the link circuit O to normal and inserts a plug of a cord circuit, the left hand plug 15 of the cord circuit O' for example, into the jack J , whereupon the cut off relay 12 of the link circuit O is operated over the following circuit: from ground by way of the resting contact of armature 78 and the said armature, resting contact of armature 80 and said armature, upper winding of the marginally adjusted sleeve relay 75, upper left hand pair of contacts of the key K^4 , the sleeve of the plug and corresponding contact of the jack J , conductor 67, and cut off relay 12 to battery. Cut off relay 12, upon energizing, removes the ring up relay 11 from in bridge of the conductors of the toll line and closes a circuit for the 33 busy lamps L' , L^9 and L^2 in the usual manner. The marginally adjusted sleeve relay 75, however is not able to energize owing to the high resistance of cut off relay 12.

The operator now inserts the other plug 35 of the cord circuit O' into the jack of one of the reserve toll service trunks and, since the said jack is similar in every respect to the jack J' , for the purpose of illustration it may be assumed that the jack J' is the one used. With the assumption as above noted, the marginally adjusted sleeve relay 75' of the cord circuit O' , and cut off relay 35 and relay 36 of repeater E energize in series, the combined resistances of relays 35 and 36 being lower than the resistance of cut off relay 12 of the link circuit O' . Upon energizing, relay 35 disconnects the toll service trunk conductors 89 and 91 from the associated toll line and connects them to the 45 heavy talking conductors of the jacks J' and J^3 at armatures 39 and 41, and at armature 40 disconnects the supervisory lamp L^4 . Relay 36, upon energizing, prepares a circuit for relay 37 at armature 42 and at armature 47 places ground on sleeve conductor 86 by way of the following path: from ground by way of the working contact of armature 47 and said armature, resting contact of armature 48 and said armature, conductor 88, and 55 the working contact of spring 93 and said spring to sleeve conductor 86, the effect of placing this ground potential on sleeve conductor 86 is to short circuit sleeve relay 75' of the cord circuit O , which relay falls back. 60 As a further result of the inserting of the

plug into the jack J' the spring 83 is forced into engagement with its associated contact, thereby closing the circuit of supervisory relay 16 of repeater D in series with the line relay of the toll first selector as follows: 70 from ground by way of the low wound supervisory relay 16, conductor 87, working contact of spring 83 and the said spring of jack J' , conductor 85, resting contact of armature 44 and said armature, and control conductor 90 to battery, by way of the line relay of the toll first selector. The line and release relay of the toll first selector now energize and prepares the switch for operation in the usual manner. 75

Supervisory relay 16, upon energizing, closes a circuit for relay 37 at armature 28. Upon energizing, relay 37 connects the impulsive relay 38 in bridge of the conductors leading to the tip and ring contacts of the jack J' , at armatures 43 and 45. Impulsive relay 38 immediately energizes over the bridge across the tip and ring conductors, of the cord circuit O' , including relay 76' and the upper winding of relay 77', and 80 closes at armature 46 a shunt around armature 44 and its resting contact. Since relay 38 is wound with fewer turns than relay 37 as can be readily seen, and since relay 37 is retarded by a heavier spring combination which has a stiff adjustment, the time that elapses after the circuit of impulsive relay 38 is closed at the working contacts of armatures 43 and 45 and before armature 44 breaks away from its resting contact, which owing to a special adjustment does not occur until armature 44 is almost 85 fully operated, is sufficient to allow impulsive relay 38 to operate, thereby placing the shunt around armature 44 and its resting contact at armature 46 before the said armature 44 has been moved out of engagement with its resting contact. As a further result of the energization of relay 37, it removes the previously pointed out short circuit from the sleeve relay 75' of the cord circuit O' at armature 48, and the said sleeve relay 75' immediately energizes and at armature 79' closes the circuit of the lower winding of relay 77'. The current through the lower winding of relay 77' 90 serves to assist the current flowing through the upper winding in series with relay 76' and impulsive relay 38 of the repeater E and the said relay 77' energizes. Relay 77', 95 upon energizing, closes a circuit for supervisory lamp L^6 at armature 81' and the said lamp becomes lighted. Relay 76' also is energized but does not perform any function at this time. 100

The operator may now throw the calling device key K^5 in such a direction as to operate the right hand springs thereof thus removing relay 76' and the upper winding of relay 77' from in bridge of the talking con- 105

- ductors, at the same time closing the following bridge across the said talking conductors: from the lower talking conductor of the cord circuit O' , by way of the working 5 contact of the lower right hand spring of key K^s and said spring, conductor 61, normally closed contacts controlled by armature 52 of the calling device switching relay 50, impulse springs of the calling device S , 10 normally closed contacts controlled by armature 53, resistance 58 associated with the secondary winding of the operator's induction coil, the secondary windings of the said induction coil, conductor 60, and the upper 15 right hand spring of the key K^s to the upper talking conductor of the cord circuit O' . Relay 77' it may be stated is now maintained energized over its lower winding.
- The operator may now manipulate her 20 calling device S in accordance with the digits of the desired number, whereupon the interruptions produced in the circuit of impulsing relay 38 are reproduced in the control circuit, including supervisory relay 25 16 and control conductor 89, at armature 46, thereby operating the automatic switches so as to cause them to connect with the desired line in the usual manner. Supervisory relay 16, being slow acting maintains its 30 armature attracted throughout the interruptions. After having finished calling the desired number, the operator restores the calling device key to normal position, thereby disconnecting the calling device S and her 35 head set from the talking conductors and placing the relays 76' and 77' in bridge of the said conductors again.
- The operator now throws the key K^s into 40 ringing position, thereby operating the upper and lower right hand springs thereof with the result that ringing current is placed on the tip and ring conductors of the jack J' and the resistance 92' is inserted into the sleeve conductor of the cord 45 circuit. In the repeater E, the low wound marginally adjusted relay 36 falls back in response to the placing of resistance 92' into the circuit, but relay 35 is maintained energized. Upon falling back, relay 36 opens 50 the circuit of relay 37 at armature 42. Upon deenergizing, relay 37 closes a multiple point in the control circuit at armature 44 and at armatures 43 and 45 disconnects the tip and ring conductors of the jack J' from the upper and lower windings of impulsing relay 55 38 and connects them to trunk conductors 89 and 91. Ringing current is now sent out over the trunk conductors 89 and 91 to ring the bridged bell at the called substation.
- When the operator restores the key K^s 60 to normal position ringing current is removed from the tip and ring conductors of the jack J' and the resistance 92' is short circuited again, whereupon relay 36 of repeater D is again energized and at armature 42 closes the circuit of relay 37. Relay 37, upon energizing, shifts the tip and ring conductors of the jack J' from the trunk conductors 89 and 91 to the upper and lower windings of relay 38 again, whereupon the said relay 38 becomes energized. 70
- When the called subscriber answers, the hereinbefore mentioned high resistance is inserted into the operating circuit whereupon the marginally adjusted supervisory 75 relay 16 deenergizes and at armature 28 opens the circuit of relay 37. Relay 37, upon deenergizing, disconnects the upper and lower windings of impulsing relay 38 and connects up the trunk conductors 89 and 91 again at armatures 43 and 45. As a further result of the deenergization of relay 37 it places ground on sleeve conductor 86 at armature 48 by way of a previously traced circuit, thereby short circuiting 80 sleeve relay 75' of the cord circuit O' . Upon deenergizing, relay 75' opens the circuit of the lower winding of relay 77', whereupon relay 77' deenergizes and extinguishes the lamp L^s to give the operator 85 answering supervision.
- The calling and called subscribers may now converse with each other in the usual manner and when the conversation is finished they both replace their receivers. 90
- When the receiver is replaced at the called substation the resistance of the control circuit is again lowered, whereupon supervisory relay 16 is again energized and at armature 28 closes the circuit of relay 37. 95 Relay 37, upon energizing, connects up the impulsing relay 38 again at armatures 43 and 45, and at armature 48 removes the short circuit from around sleeve relay 75' of the cord circuit O' . Relay 75', upon energizing, closes a circuit for the lower winding of relay 77'. Current is now flowing through both the upper and lower windings of relay 77' and the said relay, upon energizing, lights the supervisory lamp L^s 100 105 to give the operator a disconnect signal.
- When the calling subscriber replaces his receiver, the usual disconnect signal is brought in to the operator in the distant exchange and she momentarily throws her ringing key, thereby projecting ringing current out over the trunk line X . This ringing current comes in through the tip and ring conductors of the jack J and passes through the upper winding of relay 77 and 110 through relay 76. Upon energizing in response to this ringing current, relay 76 removes the shunt from around the lower winding of the marginally adjusted sleeve relay 75, whereupon the said relay energizes in series with cut off relay 12 of the operator's circuit O , and, upon so doing, 115 opens another point in the before mentioned shunt around its lower winding at armature 78, and at armature 79 closes a circuit 120 125 130
- When the operator restores the key K^s to normal position ringing current is removed from the tip and ring conductors of the jack J' and the resistance 92' is short circuited again, whereupon relay 36 of repeater D is again energized and at armature 78, and at armature 79 closes a circuit 130

for the lower winding of relay 77 by way of resistance 82. Upon energizing, relay 77 closes a circuit for the supervisory lamp L⁵ at armature 81 and the said lamp becomes lighted. The operator, upon noting the lighted condition of the lamps L⁵ and L⁶, knows that the conversation is completed and that both the calling and called subscribers have replaced their receivers and 10 she pulls down the connection.

When the plug is removed from the jack J' relays 35, 38, and 36 of the repeater E deenergize and the latter opens the circuit of relay 37 at armature 42, whereupon the 15 said relay 37 deenergizes. Supervisory relay 16 deenergizes and the automatic switches release in response to the opening of the control circuit at spring 83 and its working contact. In the cord circuit O' 20 relays 75', 76', and 77' now deenergize and the supervisory lamp L⁶ becomes extinguished.

When the plug is removed from the jack J, cut off relay 12 of the operator's circuit 25 O deenergizes and connects up the ring up relay 11, and sleeve relay 75 of the cord circuit O' deenergizes and opens the circuit of relay 77 at armature 79. Relay 77, upon deenergizing, opens the circuit of supervisory lamp L⁵ whereupon the said lamp becomes extinguished. The entire connection is now released and the apparatus restored to normal condition.

It will be noted that with the exception 35 of the upper and lower right hand springs of the key K⁴ which constitute the monitoring key and the upper and lower left hand springs of the key K⁶ which constitute the listening key, the two ends of the cord circuit O are identical and either end of the said cord circuit operates equally well in connection with a toll line jack such as the jack J or a toll service trunk jack such as the jack J'. It will be explained now in 40 a few words how either end of this cord circuit may be used to connect with a trunk which is arranged for reversed battery supervision. Taking the right hand end of the cord circuit O, for example, if we assume that the repeater E has been arranged 45 differently and that instead of the method of supervision that was described in the preceding call the said repeater had been arranged merely to reverse the direction of current flow in the tip and ring conductors of the jack J' upon the answering of the called subscriber the supervisory lamp L' would have become extinguished upon the falling back of relay 77' which falls back, 50 upon the reversal of current in its upper winding, owing to the fact that the current flowing in the said upper winding opposes that flowing in the lower winding. This method of supervision may be used in case 55 the operator has any trunks multiplied into

her position that are arranged to give reversed battery supervision.

In regard to separating one end of the cord circuit O' from the other so as to talk to one subscriber after the connection is established without letting the other subscriber hear, it may be said that it is only necessary to throw the key K⁵ in the one direction or the other depending upon which subscriber the operator desires to converse 75 with. In the link circuit O, however, this same result is accomplished in a slightly different manner. If we assume that the operator has a connection set up through the said link and that she desires to converse with the subscriber on the toll end, she throws the key K³ to calling position, which, among other things, disconnects the right hand or local end of the link circuit O, at springs 105 and 107. In case the operator desired to converse with the subscriber on the local end of the link circuit O without the knowledge of the subscriber on the toll end thereof, she may throw the key K' in such a direction as to operate the 80 upper and lower right hand springs thereof, thereby disconnecting the toll line from the link circuit O.

Provisions have been made in both the cord circuit O' and the link circuit O, whereby the toll operator may listen in and supervise a connection without causing the subscribers to hear disturbing noises and without shunting too much talking current away from its intended path. When the 95 key K² of the link circuit O, which is a combined listening and monitoring key, is thrown in such a direction as to operate the upper and lower left hand springs thereof, the operator's head set is bridged across the 100 talking conductors and ground is placed on the conductor 62, thereby operating relay 51 of the operator's head set. Relay 51, upon energizing, opens the primary windings of the operator's induction coil at armature 57; disconnects the operator's receiver from the mid point of the secondary winding at armature 56; and at armature 55 disconnects the lower terminal of the secondary winding of the induction coil from 105 conductor 63 and connects it again to the same conductor through the operator's receiver. It will be seen now that any current in order to reach the operator's receiver must pass through the upper and lower secondary winding of the induction coil in series and resistance 58, and since the primary windings of the operator's induction coil are open at this time there is 110 a high impedance to voice currents so that only a minimum amount of the voice currents are shunted away from their normal path when the monitoring key is thrown. When the monitoring key is restored, relay 51 deenergizes and restores the circuits in 115 120 125 130

the operator's head set to normal. The conditions are obviously the same when the key K^4 of the cord circuit O' is thrown to the monitoring position.

5 In case the operator wishes to listen in on the connection and finds that she is unable to hear well enough when the monitoring key is thrown and does not wish the talking parties to be disturbed by noises which 10 may be present in switchroom, she throws the listening key in the usual manner after having short circuited her transmitter by operating the spring 59 associated therewith. This spring may be operated by either a 15 key or a push button.

As has been mentioned before, the jacks J^2 and J^3 , which are multiples of the jacks J and J' , are located at the night operator's position. This operator has multipled into 20 her position all the toll lines and all the toll service trunks that terminate in the several day operators' positions, it being well known of course that as the usual thing the traffic is very much lighter at night than 25 during the day and one night operator will suffice whereas several day operators are required. The night operator among other things must be informed when a call comes in over any toll line. This is accomplished 30 by providing a lamp switching key for each toll line jack in the night operator's position. One of these keys is shown associated with the jack J^2 and when operated disconnects the line lamp L associated with 35 the link circuit O and connects up the line lamp L^8 associated with the jack J^2 .

Having described my invention, I will point out in the appended claims what I consider to be new and desire to have 40 protected by Letters Patent.

What I claim as my invention is:

1. In a telephone system, an operator's switchboard, toll lines and local trunk lines terminating at said switchboard, a group of 45 link circuits for connecting said toll lines and local trunk lines, each link circuit being adapted to connect only a particular one of said toll lines with a particular one of said local trunk lines, and a second group 50 of link circuits for connecting said toll lines and local trunk lines, each link circuit of the second group being adapted to connect any toll line with any local trunk line.

2. In a telephone system, a plurality of 55 toll lines extending to a distant exchange, a plurality of toll service trunks for connecting with local subscribers' lines, a plurality of operator's link circuits permanently associating said toll lines and toll 60 service trunks together in pairs, multiple jacks for said toll lines and toll service trunks, and a plurality of operator's cord circuits through the medium of which said toll lines may be connected with toll service

trunks other than the ones with which such 65 toll lines are paired.

3. In a telephone system, a plurality of toll lines extending to a distant exchange, a plurality of local trunk lines, operator's link circuits for connecting said toll lines and local trunk lines, each link circuit being individual to a particular toll line and to a particular local trunk line, multiple jacks for said toll lines and local trunk lines, and a plurality of cord circuits for connecting said toll lines and local trunk lines via 70 said jacks at the option of the toll operator.

4. In a telephone system, a toll line extending to a distant exchange, a local trunk line, an operator's link circuit individual to 80 said toll line and local trunk line for connecting the two together, a ringing key in said link circuit for signalling a distant operator to obtain a desired toll connection, and a series of operator controlled automatic switches for connecting said local trunk line with a local subscriber's line.

5. In a telephone system, a toll line extending to a distant exchange, a local trunk line, an operator's link circuit individual to 85 said toll line and local trunk line for connecting the two together, a ringing key in said link circuit for signalling a distant operator to obtain a desired toll connection, a series of operator controlled automatic 90 switches for connecting said local trunk line with a local subscriber's line, and supervisory signals in said link circuit controlled by the distant operator and by the subscriber on the local line.

6. In a telephone system, an operator's switchboard, a cord circuit and a spring jack thereat, an automatic switch, a trunk terminating in one end in said jack and at the other end in said switch, a supervisory signal associated with said cord circuit, a repeater interposed in said trunk, means including said cord circuit and said switch for extending a connection by way of said 105 trunk line and repeater to a desired line, a relay in said repeater, means responsive to the answering of the subscriber on said desired line for operating said relay to alter the potential of the sleeve conductor of said jack, and means responsive thereto for operating said supervisory signal.

7. In a telephone system, an operator's switch board, an automatic switch, a repeater, a trunk extending from said switch board to said switch by way of said repeater, means including said trunk and said switch for setting up a connection from said switch board to a desired line, said trunk being divided into two sections at said repeater, a control conductor separate from the talking circuit of said trunk and extending from said repeater to said switch, a repeating relay in said repeater, means for 110 115 120 125

controlling said relay over the two sides of the section of said trunk between said switch board and said repeater in series to send impulses over said control conductor

5 to operate said switch in extending a connection, a second relay in said repeater, and means for operating said second relay over said control conductor responsive to the an-

swering of the called subscriber to disconnect said repeating relay from the talking 10 circuit and to unite the two sections of said trunk.

In witness whereof, I hereunto subscribe my name this 20th day of July, A. D. 1921.

WILLIAM A. BENSON.
